STOP MECHANISM FOR KNITTING MACHINES

Jacob Wachsman and Michael Wachsman,
Brooklyn, N. Y.

Application June 18, 1937, Serial No. 148,854

2 Claims. (Cl. 66—163)

This invention relates to stop mechanisms for knitting machines of the type disclosed in Reissue Patent 19,069, February 6, 1934 to Jacob Wachsman and has also reference to Patent 5 2,080,903, May 18, 1937 to Michael Wachsman.

Stop motions or mechanisms and parts thereof of the type disclosed in these two patents are well known in the art and need not be described in detail.

10 The said reissue patent discloses the combination of two thread supporting levers with an overhanging fixed guard. One of the levers is a spring held or tension knot detector lever. The other lever is a gravity actuated end detector lever. The overhanging fixed guard serves the purpose of preventing a rise of the end detector lever to an electric circuit closing portion because of a mere slack in the thread. Where such a slack occurs the thread will be lifted by the end 15 detector lever up against the guard into a position in which the thread straddles the lever and thus prevents the latter from rising by gravity into a still higher position in which said lever makes a contact to close an electric circuit which 20 in turn causes the knitting machine to stop.

In practise the guard also functions as a self-threading member for the stop motion in that the thread is placed upon or threaded upon the 25 levers by merely placing the thread upon the guard. The latter has a forwardly and downwardly inclined member. The thread therefore slides down the guard into position upon the levers without any further attention by the operator.

30 The said other Patent No. 2,080,903 discloses a tension lever for electric stop motions in which the selfthreading feature is incorporated in the lever itself. For this purpose the lever has an upwardly inclined guard member. The thread is thrown 35 upon or placed against this member and then slides down into position upon the lever.

The object of the present invention is to provide a stop motion which embodies a selfthreading guard member according to the said reissue 40 patent together with certain features which are disclosed in the said other patent. The result is a new simple stop mechanism embodying certain improved features not found in either of the 45 said two patents.

50 In the accompanying drawing Fig. 1 is a side view partly in section and with parts omitted of a stop mechanism embodying the invention.

Fig. 2 is a plan view thereof.

Fig. 3 is a detail view of a contact spring.

55 In the drawing the reference numeral 6 de-

notes a housing or box made in any suitable manner and provided with a lug 7 whereby it may be attached to a knitting machine. 8 denotes a contact spring which is secured to a fixed electric terminal 9 suitably insulated from the box. The 5 terminal 9 is as usual included in the electric stop circuit not shown. In the sides 10 of the box are notches 11 for pivoting the spring held lever 12 which inside the box is provided with a contacting heel 13 adapted to contact the spring 8 so as to close the electric circuit. The lever 12 is held in a normal operative position by a spring 14 having adjusting means 15. The contact spring 8 may conveniently be divided as at 16 to permit passage of the spring 14 as will be 10 explained hereinafter.

The lever 12 has two forwardly extending arms 17, 17 which are covered with porcelain fingers 18, 18. The latter are shaped to provide thread supporting portions 19 and overhanging noses 20 20 which form a thread enclosing space 21 with an entrance for the thread at 22.

At 24 there is secured to the lug 7 a guard member which preferably consists of a piece of wire bent to form forwardly and downwardly 25 extending threading portions 25 which are then bent back to form horizontal thread retaining portions 26. The latter are then bent upwardly to form lateral stop portions 27. The ends of the guard may be attached by a screw or rivet at 24. 30

Fig. 1 shows the part in normal operating position with the thread 30 placed upon the fingers 18 underneath the portions 21 of the guard. The spring 14 will be adjusted to just balance the weight and the pull of the thread upon the 35 lever. When a knot or other obstruction occurs in the thread, the latter can no longer run over the porcelain fingers. The thread then pulls down the lever 12 into a position in which the thread slips off the porcelain fingers and the 40 contact heel 13 is raised against the force of the spring 14. This position is indicated by the dotted line 32. The spring now pulls the lever down into a position indicated approximately by the other dotted line 34 and the contact heel now 45 engages the spring 8 and closes the electric circuit in a well known manner which need not be described herein. The knitting machine then stops. The thread supporting lever is now held by the spring 14 against the lateral stop portions 50 27 on the guard and as seen in Fig. 1 the thread may now be put back into the stop motion by dropping it upon the lever in front of the inclined guard portion 25 and then pulling the lever down into normal position. As the lever 55

moves down the thread will slide down the guard and in under the nose 36 thereof into the enclosed space 21 of the finger 18.

When a slack occurs the lever will be moved 5 upward by the spring 14 but not high enough to cause contact to be made because the guard portions 21 overlie the thread and prevent rise of the lever into contact making position.

If the thread breaks or runs out the weight 10 thereof will be removed from the lever which will immediately be pulled down into contact making position by the spring 14.

It will be noted that when a knot occurs on the 15 thread the lever will first be moved down into position 32 before the spring can move it into contact making position at 34. Thus there will be a hardly perceptible delay before contact is made. Such a slight delay is practically of no importance. It may be avoided however by providing 20 the contact spring with an upstanding finger 38 so that when the lever is moved down by the thread contact will be immediately made with said finger 38. It will be understood that inasmuch as the upper end of the spring follows the 25 movement of the contact heel it will necessarily pass across the contact portion of the spring 8, that is it will pass through the space 16 provided in the spring.

The construction herein disclosed includes several advantages over prior structures. In the 30 first place, the entire mechanism is of extreme simplicity which makes for accessibility, cleanliness and efficient operation. The thread enclosing space 21 in combination with the overhanging guard is of decided advantage. It is a well known fact that the thread in knitting machines does not run in a steady straight line but vibrates and bobs up and down due to the high speed of the machines, the variation in diameters of the 35 bobbins and that in the summer time when windows are open in the plant, the threads are blown about and are thus apt to be blown into or against the stop mechanisms. In this instance the thread has space within the enclosed space 21 which on the one hand permits free movement 40 of the thread and eliminates friction and strain. On the other hand the porcelain fingers are so

shaped that the thread is confined and cannot be blown out of position.

Another advantage is that when the lever has been raised by the spring into the position indicated at 34, it forms a wide angle with the guard 5 which facilitates replacing and rethreading.

We claim:—

1. In a knitting machine a stop mechanism under control of a travelling thread, a circuit closer unit comprising a housing, a fixed electrical terminal secured thereto, a single spring held lever pivoted in said housing including thread receiving and supporting fingers, said lever serving both as a knot detector and an end detector for a thread placed upon said fingers, a spring 15 for balancing said lever in a normal operative position against the weight of a thread placed upon said fingers, a contact heel on said lever, said spring continuously tending to move said contact heel into engagement with the said fixed 20 terminal and a fixed guard on said housing to hold the lever against engaging said terminal so long as a thread lies upon the fingers of the lever.

2. In a knitting machine a stop mechanism under control of a travelling thread, a circuit closer 25 unit comprising a housing, a single thread supporting lever pivoted in said housing, porcelain members on said lever forming thread receiving fingers and overhanging noses spaced from said fingers to form thread enclosing spaces, means 30 for balancing said pivoted lever in normal operative position against the weight of the thread placed upon said thread supporting fingers, a fixed guard on said housing having horizontally disposed thread restraining portions in cooperative 35 relation with the said thread enclosing fingers and noses, stop portions on said guard which the said lever is adapted to abut when it is swung above its pivot, an electric terminal spring contact within the housing and a contact 40 heel upon said lever for contacting the said spring contact when the said lever is moved above or below its pivot by the removal of the thread from the said thread supporting fingers.
